[57] CLAIM

The ornamental design for wood lattice basket, as
shown and described.

DESCRIPTION

FIG. 1 is a front elevational view of the ornamental
wood lattice basket showing my new design, the rear
elevational view being identical;

FIG. 2 is a right side elevational view thereof, the left
side elevational view being identical;

FIG. 3 is a top plan view thereof; and,

FIG. 4 is a bottom plan view thereof.

FIG. 1

FIG. 2

FIG. 3

FIG. 4
